UNITED STATES PATENT OFFICE.

EUCHER GRES, OF TOMBSTONE, ARIZONA TERRITORY, ASSIGNOR OF ONE-HALF TO SOLOMON ISRAEL, OF SAME PLACE.

SPRING-ROLLER.

SPECIFICATION forming part of Letters Patent No. 374,060, dated November 29, 1887.

Application filed August 17, 1886. Serial No. 211,168. (No model.)

To all whom it may concern:

Be it known that I, EUCHER GRES, a citizen of the United States, residing at Tombstone, Cochise county, Territory of Arizona, 5 have invented a new Adjustable Solid Spring-Roller for Window-Shades, of which the following is a specification.

My invention relates to the class of spring-actuated rollers for window-shades wherein a 10 casing secured to the curtain-roller incloses a drum and spiral spring, one end of said spring being attached to the pivot or shaft on which said casing turns, and the other end of the spring being attached to the casing and roller 15 to revolve the same and wind the curtain upon the roller, while the shaft of the drum is held stationary upon the bracket, a suitable catch being employed to connect the pivot or shaft and casing and lock them together at any required position at which the curtain is to be 20 held upon the roller.

My invention consists in certain constructions and combinations of parts, hereinafter particularly described, and designated by the 25 claims, with reference to the accompanying drawings, wherein—

Figure 1 is a perspective of the roller-shade and fixtures complete. Fig. 2 is a perspective of the inner face of the left-side 30 bracket, and Fig. 3 a similar view of the inner face of the right-side bracket; Fig. 4, a side elevation of the metal end cap and flange to be applied to one end of the roller, and Fig. 5 a similar representation of the end cap and 35 casing for the spring and drum to be secured to the other end of the shade-roller. Fig. 6 is a perspective of the end cap and casing shown in Fig. 5; Fig. 7, a perspective of said end cap and casing, with the spring and drum, with 40 their connections, inclosed within said casing; Fig. 8, a perspective of the drum, the spring, and the arbor removed from the casing; and Fig. 9, a perspective of the key for winding the spring to the required tension.

45 The brass or metal circular case A is secured to the right-hand end of the wooden roller. The disk B is secured to the inside of said case, and together they revolve around the fixed pivot d, which passes through central holes in 50 the disk and the case and enters a hole in the end of the wooden roller C. The pivot is made

stationary by its square head m' being placed in the bracket D, and secured by a screw, n. One end of the spring E, (of blue steel, such as is used for watches and clocks,) is secured 55 to the pivot d, close to and touching the inner surface of the disk B. The other end of the spring passes through the aperture b made in the shoulder a of case A. (See Figs. 6 and 5.) The edge of the disk B, resting upon the shoulder a, referred to, and secured in that position by screws entering the holes f f, confines the spring in the space of the width of said shoulder a, between the disk B and the end of the case A. Thus one end of the spring e being 60 secured to the stationary pivot and the other end to the case A, in which is secured the disk B, and the said case being secured to the wooden roller, the untwisting pressure of the spring causes these parts and the roller to 65 revolve when free to do so. The size and strength of the spring depend on the size and weight of the shade. The combination that stops the action of the spring is encircled by the flange of the disk B. (See Fig. 7.) The pin g is passed 70 through an enlargement, d', near the end of the pivot d, and is bifurcated at the point, into which bifurcation is inserted the lever h, which acts upon the bar i by the connecting wire rod i. The bar i is also attached to the butt-end 75 of the pin g, and secured by a small pivot.

In the flange k are three slots or apertures at equidistance apart, one of which, l, is shown, and into which a rounded projection or catch, i', formed upon the bar i, drops and stops the 80 action of the spring. Lowering the shade releases the catch (when it is in working order) there being no resistance made by the lever h above; but the reverse pressure, caused by raising the shade, meets with resistance below, 85 made by the butt-end of the fixed pin g, which presses the bar i more firmly against the side of the flange k, when the catch i' is in one of the slots formed in the flange k. In rapid revolution of the flange the rounded projection 90 or catch i' upon the bar i slides along the side of the flange k without dropping into the slots; but when it revolves slowly, the catch i' drops into one of said slots and action is stopped.

To the small end of the lever h is attached 95 the piece of wire m, which extends below the combination-case for the purpose—by pulling

it—of releasing the catch, when pulling the shade will not do it. The key, Fig. 9, fits the head of the pivot *d*, and by winding to the left will strengthen the spring.

5 The construction above described will provide a secure connection between the fixtures and the end of the roller, which latter may be perfectly solid, and large-sized tacks may be employed at *o* to pass through the part *a'* of the casing *A*, and through the part *a²* of the flanged end piece, *A'*, at the left-hand side of the roller. A pintle, *d'*, upon the bracket *D'*, at the left-hand side of the roller *C*, passes through the end of the flanged end piece, *A'*, and supports the end of the roller.

15 I claim as my invention and desire to secure by Letters Patent—

1. A spring-fixture for curtains, consisting of the casing *A*, the disk *B*, secured in said 20 casing, and having a flange, *k*, provided with a slot or slots, *l*, the shaft *d*, passed through said casing and disk, whereby such parts may turn on the shaft, the support *g*, connected with the shaft, the bar *i*, connected to such 25 support, and having a projection, *i'*, to enter the slot *l*, the lever *h*, and the rod *j*, connecting the bar *i* with the lever *h*, substantially as and for the purposes specified.

2. The combination, in a curtain-fixture, of a casing adapted for connection with the curtain-roller, and having a flange or plate fixed rigidly to it and provided with a notch or notches, *l*, a spring for turning said case, a bar, *i*, having a projection fitted to enter the notch or slot *l*, a lever, *h*, a connection between 30 said lever *h* and bar *i*, and non-rotating supports for said lever *h* and bar *i*, whereby the casing may be held against or subjected at will to the rotating action of the spring, substantially as and for the purposes specified.

3. The combination of the curtain-roller, the disk fixed with reference to said roller, whereby a turning of the disk will effect a turning of the roller, a flange, *k*, provided on said disk, and having a slot or slots, *l*, a shaft, *d*, inserted 45 through said disk and serving as an axis on which said disk may turn, a support, *g*, a bar, *i*, pivoted to said support, and having a projection, *i'*, to enter the slot *l* of flange *k*, the lever *h*, and connection *j*, all substantially as 50 and for the purposes specified.

EUCHER GRES.
